TELEPRINTER TRANSMITTER FOR
PERFORATED TAPE RECORDS

Herbert Wüsteney, Kladow, Germany, assignor
to Siemens & Halske, Aktiengesellschaft, Sie-
mensstadt, near Berlin, Germany, a German
corporation

Application October 5, 1950, Serial No. 188,613
In Great Britain October 19, 1949

12 Claims. (Cl. 178—17)

1

This invention is concerned with teleprinter transmitter apparatus provided with perforated tape records.

The transmitter shaft in known apparatus of this class is rotated by a drive motor through the medium of gear wheels and a mechanical clutch which is usually a friction type clutch. Such a driving arrangement puts considerable stresses on the gear wheels and results in noisy operation during transmission pauses, i. e., during periods when the transmission of signals is interrupted.

The principal object of the invention is to avoid the above indicated drawbacks by directly coupling or gearing with the shaft of the drive motor the transmitter shaft which carries cam means for periodically actuating transmitter contacts and by short-circuiting such contacts during transmission pauses while the motor is running.

The direct coupling of the transmitter shaft with the motor eliminates the usual gear wheels and clutch means, thus avoiding noisy operation, reducing the load on the motor, and therefore also reducing the motor rating. The invention, in addition, simplifies the structural aspects of the transmitter.

The above noted principal object of the invention is realized in a preferred embodiment by utilizing for the actuation of the short-circuiting contacts the means which is employed for advancing the perforated tape record. This means may be in the form of a shifting lever which is put in locking position once during each revolution of the transmitter shaft, at the conclusion of each tape advance stroke, by a control cam disposed on the transmission shaft. The shifting lever may be held in this locking position, depending on operating criteria which may require interruption of the transmission of signals, including, for example, the relative tensioning or slackening of the perforated tape record or the termination thereof, or the stopping of the drive motor, or the actuation of the current supply switch to "Off" position. The invention is of course not inherently limited to such embodiment. Its objects may be realized by different means, for example, by the use of a plurality of contacts arranged in parallel circuits and by actuating such contacts depending on the respective operating criteria.

The above noted principal object and additional objects and features of the invention will be described more in detail with reference to the accompanying drawings. In these drawings,

Fig. 1 shows an embodiment of the invention 65 tape 1. It will be observed that the shift lever

2

representing in simplified diagrammatic manner essential parts of a transmitter for accomplishing the control of the shifting lever in the manner referred to above; and

Fig. 2 illustrates in similar diagrammatic manner essential structural parts for interrupting the transmission in a two-way teleprinter operation.

Numeral 1 designates the transmitter shaft which is directly geared or coupled with the shaft 10 46 of the drive motor 35, e. g., by suitable means shown in the form of gears 36/37—38/39, to give an example. The pivotally mounted shift lever for advancing the perforated tape record 7 is indicated at 3. Numeral 8 is a control bar for holding the shift lever 3 in locked position to prevent advance of the tape record 7, thereby interrupting the transmission of signals when such interruption is required. The transmitter shaft carries 15 a plurality of cams, e. g., five cams, one such cam being indicated at 32, each cam being provided for actuating transmitter contact springs such as indicated at 31. The shaft also carries a control cam 2 which puts the shift lever 3 in locking position at the conclusion of each advance stroke of 20 the perforated tape record, thereby also operatively actuating the contact springs 42 which short-circuit the transmitter contacts 31. The generally T-shaped shift lever 3 carries on one of its arms the pawl 4 which coacts with the ratchet 5 provided on the shaft carrying the sprocket 6. The latter coacts with the perforated tape record 7 and shifts it by one step responsive to each actuation of the ratchet 5 by the pawl 4. The levers or feeler arms (not shown to avoid extraneous details) coacting with the tape record 25 7 are in suitable and known manner alternately lifted from and dropped upon the tape during the advance thereof to sense the markings on the tape in accordance with known practice.

40 The control bar 8 serves the purpose of freeing the shifting means for the tape record, or locking it against operation, as may be required. A spring 9 is provided for biasing the control bar 8 to the right in operating position, in which the shifting means, that is, the shift lever 3 with its pawl 4 and angular extension 11, is free to operate because the angular extension 11 is not impeded in its motion. However, if the control bar is moved to the left, the ear 10 carried thereby will be placed underneath the angular extension 11 of the shift lever 3 and thus will lock it against counterclockwise displacement, holding its lower end away from the cam 2 and thereby stopping the periodic advance of the record 45 7. It will be observed that the shift lever

3 is locked with the pawl 4 in position of full advance of its operating stroke, thus positively locking the tape record 7 against further advance. The contact springs 12 are closed during this phase of the operation and short-circuit the transmitter contacts 31. The transmission line is indicated at 40. The signal transmission under control of the tape record 7 is thus interrupted while the rotation of the transmitter shaft continues.

Current is supplied to the drive motor 35 over a suitable switch 41 which is connected with the switch arm 13 by the shaft 42. When this switch arm is placed into the "off" position, disconnecting current, its cam 14 will move the control bar 8 to the left, thus placing the ear 10 underneath the angular extension 11 of the shift lever 3 to hold the shift lever in locked position, into which it is moved at the conclusion of each advance stroke by the cam 2, as described before; but when the switch arm 13 is placed into the "on" position, in which it is shown, current will be supplied to the motor to start operation, and the control bar 8 will be free to move to the right, thus freeing the shift lever 3 for operative actuation by the cam 2. If desired, auxiliary contact means (not shown) may be actuated by the switch arm 13 to close at this moment a point in the transmitter or line circuit and to short-circuit the manual transmitter means of the corresponding teleprinter apparatus.

The transmission of the signal impulses in accordance with the markings of the perforated tape record cannot begin until the drive motor has attained a predetermined speed of rotation. When this speed is attained, the centrifugal governor 15 carried by the motor shaft 16 or by the motor armature causes displacement of an operating element, e. g., of the pin 17, to the left, as shown in the drawing, thus freeing the pivotally mounted lever 18 so as to permit displacement of the control bar 8 to the right under the pull of the spring 9. This operation takes place after partial angular clockwise displacement of the shift lever 3 under control of the cam 2. The shift lever 3 is freed for its full displacement by the removal of the ear 10 of the control bar 8 to the right, away from the angular extension 11 of the shift lever. This operation is accomplished at the moment when the shift lever 3 is displaced clockwise into its terminal stroke position, being actuated into this position by the operation of cam 2. The transmission of the signals therefore always begins with a full symbol signal impulse.

Increasing tension placed on the perforated tape record 7 carries the stirrup 19 to the left, and the latter presses on the control bar 8 by means of its bracket 33, to move the bar into its locking position with the ear 10 disposed underneath the angular extension 11 of the shift lever. If the tape record 7 slackens, the stirrup 19 will move to the right, and the control bar 8 follows at the moment when the angular extension 11 of the shift lever 3 is lifted consequent to clockwise displacement of the shift lever by the cam 2 at the conclusion of an advance stroke of the tape record. Special biasing means for the stirrup is not absolutely required but may be provided, if desired.

When the perforated tape record reaches its end, the lever arm 20, which rests thereupon lightly by spring bias, will drop upon the pivotally mounted crank arm 21 through a slot in the tape guide (not shown), moving the crank arm clock-

wise to shift the control bar 8 to the left, thereby stopping the transmission by locking the shift lever 3 in terminal stroke position into which it has been placed by the cam 2. The lever arm 5 20 is preferably journaled in the bracket which holds the tape in its guide and is lifted with such bracket when a new tape record is inserted.

In order to avoid the transmission of distorted signals, incident to the slowing-down of the motor responsive to failure of the current supply 10 for any cause, and to avoid the danger of stopping the transmitter with interrupted line circuit, there is provided a magnet 22 whose winding is connected in parallel with the motor circuit, thus keeping the magnet energized and the armature 23 normally attracted. If the current supply fails for any cause, the magnet 22 de-energizes, releasing the armature 23, and the latter is positioned incident to the next full stroke 15 20 operation of the shift lever 3 underneath the angular extension 11 in the same manner as the ear 10 of the control bar 8, to hold the shift lever locked against further operation.

The signal transmission may be interrupted, in 25 a two-way operation, by the control means shown in Fig. 2, for the purpose of receiving signals from a remote station. On the transmitter shaft 1 is for this purpose provided the cam 24 in which is formed a depression for the lever 25 which 30 may fall into it just before the cam 2 (Fig. 1) completes the clockwise stroke displacement of the shift lever 3. The lever 25 is normally held in inoperative position, against falling into the notch in the cam 24, by a magnet 26 whose winding 35 may be disposed in the line circuit indicated at 45. In case the remote station should send signals while signal impulses are being transmitted in accordance with the perforated tape record 7, the line circuit will be interrupted and 40 the magnet 26 will become deenergized. The lever 25 may now drop into the notch in the cam 24, moving thereby counter-clockwise and lifting the pawl 27 from engagement with a notch in the segment-shaped locking member shown at the right of Fig. 2. This locking member, which is 45 mounted on the shaft 42 carrying the switch arm 13 (Fig. 1), is therefore permitted to move counter-clockwise under the pull of the spring 29 and places its portion 28 underneath the pawl 27. 50 The switch arm 13 rotates with the locking member into the "off" position, in which current is disconnected, and the control bar 8 is moved into locking position to the left, as already described. The shift lever 3 is therefore held against operation, and the transmission under the control of 55 the perforated tape record 7 is interrupted to permit receiving signals from the remote station.

Rotation of the switch 13, Fig. 1, manually into "off" position will also rotate the member 30 60 shown in Fig. 2, which is resiliently interlocked with the locking segment 28, and the upper edge of member 30 will lift the pawl 27 from the notch in member 28, thereby cancelling the interlock of the lever 25 with the switch shaft.

Changes may be made within the scope and spirit of the appended claims.

I claim:

1. A perforated tape record signal transmitter of the class described comprising a drive motor, 70 a transmitter shaft controlled by said drive motor, transmitter contacts, cam means on said transmitter shaft for periodically actuating said transmitter contacts, said transmitter shaft being directly coupled with the shaft of said drive motor, and contact means for short-circuiting said

transmitter contacts to interrupt transmission under control of said perforated tape record while continuing operation of said drive motor.

2. The transmitter defined in claim 1, together with lever means for periodically advancing said perforated tape record, said lever means controlling said contact means for short-circuiting said transmitter contacts.

3. The transmitter defined in claim 1, together with means forming a shift lever for periodically advancing said perforated tape record, cam means carried by said transmitter shaft for moving said shift lever into locking position once during each revolution of said shaft, said shift lever controlling said contact means for short-circuiting said transmitter contacts, and means for holding said shift lever in locked position depending on predetermined operating criteria of said transmitter.

4. The transmitter defined in claim 1, together with means forming a shift lever for advancing said perforated tape record, cam means carried by said transmitter shaft for moving said shift lever into locking position once during each revolution of said shaft, a control bar for locking said shift lever in locking position, and means controlled by said perforated tape record for actuating said control bar.

5. The transmitter defined in claim 1, together with means forming a shift lever for advancing said perforated tape record, cam means carried by said transmitter shaft for moving said shift lever into locking position once during each revolution of said shaft, a relay disposed in the motor circuit, said relay being normally energized, and means operated by said relay responsive to deenergization thereof for holding said shift lever in locked position.

6. The transmitter defined in claim 1, together with means forming a shift lever for advancing said perforated tape record, cam means carried by said transmitter shaft for moving said shift lever into locking position once during each revolution of said shaft, a control bar for locking said shift lever in locking position, a main switch, and means operated by said main switch upon switching it to off position for actuating said contact bar to hold said shift lever in locked position.

7. A perforated tape record signal transmitter comprising a transmitter shaft, a motor for operating said shaft, a shift lever, drive means operated by said shift lever for advancing said perforated tape record, cam means carried by said transmitter shaft for moving said shift lever into locking position once during each revolution of said shaft, means forming a control bar carrying an extension for holding said shift lever in locked position, a main switch for said transmitter, a stirrup for tensioning said tape record, a sensing lever coacting with said record, a speed governor for said motor, and means governed, respectively, (a) by said main switch in off position thereof;

(b) by said tensioning stirrup depending on the tension of said tape record; (c) by said sensing lever upon exhaustion of such record; and (d) by said speed governor upon slowing up of said motor, for actuating said control bar.

8. The transmitter defined in claim 7, together with means governed by interruption in the line circuit for actuating said control bar.

9. The transmitter defined in claim 7, together with a magnet having a winding disposed in the circuit of said motor, and an armature controlled by said magnet for coaction with said shift lever to hold said shift lever in locking position responsive to deenergization of said magnet.

10. The transmitter defined in claim 7, disposed in a circuit arranged for two-way operation, together with means for sensing current interruptions in the line circuit, means controlled by said sensing means for switching off said main switch to cause such switch to actuate said control bar to hold said shift lever in locked position.

11. In a perforated tape record transmitter of the class described which is disposed in a line circuit arranged for two-way signalling, a shift lever for periodically advancing said perforated tape record, an electromagnet having a winding disposed in said line circuit, a main switch, a control bar, means controlled by said electromagnet responsive to a predetermined current condition in said line circuit for actuating said main switch, and means operated by said main switch for actuating said control bar to lock said shift lever so as to stop the advance of said perforated tape record.

12. In a perforated tape record transmitter of the class described which is disposed in a line circuit arranged for two-way signalling operation, a shift lever for periodically advancing said perforated tape record, motor means for operating said shift lever, an electromagnet having a winding disposed in said line circuit, a main switch, a control bar, means controlled by said electromagnet responsive to a predetermined current condition in said line circuit for actuating said main switch to disconnect current from said motor, and means operated by said main switch in off position thereof for actuating said control bar to lock said shift lever so as to hold said perforated tape record in predetermined position of advance thereof.
